SUCTION CLEANER TANK HEAD UNIT

Francis D. Dolan, Toledo, Ohio, assignor to The American Floor Surfacing Machine Company, Toledo, Ohio, a corporation of Ohio

Application June 29, 1956, Serial No. 42,082

Term of patent 14 years

(Cl. D9—2)

FIG. 1.

FIG. 2.

FIG. 3.

Fig. 1 is a top perspective view of a suction cleaner tank head unit embodying my new design;

Fig. 2 is an enlarged side view thereof, and

Fig. 3 is an enlarged top plan view thereof.

The dominant features of my design reside in portions shown in full lines.

I claim:

The ornamental design for a suction cleaner tank head unit, substantially as shown and described.
